(57) **CLAIM**

The ornamental design for a snow chain as shown and described.

DESCRIPTION

FIG. 1 is a perspective view of a snow chain showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof.

The snow chain is shown with a symbolic break in its length. the appearance of any portion of the snow chain between the break lines forms no part of the claimed design.

1 Claim, 8 Drawing Sheets
